UNITED STATES PATENT OFFICE.

THOMAS B. JACKSON, OF LOCK NO. 4, PENNSYLVANIA, ASSIGNOR OF ONE-THIRD TO MARY BUMER AND ONE-THIRD TO LEONHARD DARR, OF MONESSEN, PENNSYLVANIA.

FIRE-SHUTTER.

No. 829,839.

Specification of Letters Patent.

Patented Aug. 21, 1906.

Application filed March 14, 1906. Serial No. 306,046.

To all whom it may concern:

Be it known that I, THOMAS B. JACKSON, a citizen of the United States of America, residing at Lock No. 4, in the county of Washington and State of Pennsylvania, have invented certain new and useful Improvements in Fire-Shutters, of which the following is a specification, reference being had therein to the accompanying drawings.

- 10 This invention relates to certain new and useful improvements in fire curtains or shutters; and the invention has for its primary object the provision of a novel structure for housing a curtain or shutter above 15 a window, door, or the like openings, also novel means for automatically actuating the curtain or shutter to instantly protect the window, door, or opening should fire occur in the vicinity of the same.
- 20 Another object of the invention is to provide a curtain or shutter for a window or door which will be normally protected from rough and stormy weather and which will not interfere with the movement of the sashes of 25 a window or the door of a doorway.

A further object of this invention is to provide a curtain or shutter which will be automatically actuated or released to protect a window-frame or doorway should a fire occur 30 in the vicinity of the same, thermostatic means being employed for releasing the curtain or shutter, while the force of gravity is employed to actuate or operate the same.

A still further object of this invention is to 35 provide a curtain or shutter that can be readily used in connection with various types of buildings for protecting the exposed wood-work thereof, my improved curtain or shutter being neat in appearance, whereby it will 40 enhance the general appearance of a building and not detract therefrom.

With the above and many other objects in view, which will more readily appear as the nature of the invention is better understood, 45 the same consists in the novel construction, combination, and arrangement of parts to be hereinafter more fully described and claimed, and, referring to the drawings accompanying this application, like numerals of reference 50 designate corresponding parts throughout the several views, in which—

Figure 1 is a front elevation of a window-frame equipped with my improved fire curtain or shutter. Fig. 2 is a similar view illustrating the fire curtain or shutter closed 55 and a portion of its housing in section. Fig. 3 is a vertical sectional view taken on the line *xx* of Fig. 2 looking in the direction of the arrow of said figure. Fig. 4 is a side elevation of the same. Fig. 5 is a cross-sectional view 60 of a roller used in connection with my improved curtain or shutter, and Fig. 6 is a cross-sectional view taken on the line *yy* of Fig. 2.

In order that the application of my improved fire curtain or shutter to a building 65 may be readily understood, I have illustrated a portion of a building 1 and a window-frame 2.

To put my invention into practice, I secure 70 to the building 1 at each side of the window-frame two vertical guide-plates 3 3, said plates being secured to the building by nails 4 or like fastening means. At the upper ends of the guide-plates 3 3 and slightly to one 75 side thereof are mounted metallic brackets 5 5, said brackets being secured to the building similar to the plates 3 3. In the brackets 5 5 is journaled a roller 6, preferably constructed of metal and covered with asbestos 7 or similar non-fusible material. Attached to the roller 6, as at 8, by suitable fastening means is an asbestos curtain 9, said curtain being of a length corresponding to the window-frame 2. The curtain 9 is provided with a trans- 85 verse metallic stiffening-strip 10 centrally of its length, said strip being riveted or otherwise secured to the curtain, as at 11. The lower edge of the curtain is provided with metallic stiffening rib or gutter 12, which in- 90 termediate its ends is cut away, as at 14. The rib or gutter serves functionally to guide the curtain 9, to retain the curtain in shape, and as a receptacle or rest for the weight, which will be presently described. The cur- 95 tain is adapted to travel between the guide-plates 3 3, and the ends of the rib or gutter 12 and the strip 10 are adapted to ride behind said plates and maintain the curtain in its proper form or shape.

Adjacent to one end of the roller 6 is at- 100 tached a cable or cord 15, carrying a weight

16, said weight being adapted to rotate the roller 6 when the curtain 9 is operated to protect the window-frame 2. Incasing the roller 6 and the brackets 5 5 is a housing 17, said 5 housing being constructed of sheet metal and secured to the building 1 by nails 18 or like fastening means. The ends of the housing 17 are bent inwardly, as at 19, to shield and protect the brackets 5 5, while the one 10 end of said housing is provided with a depending arm 20, carrying pierced lugs 21 21, between which is journaled a pulley 22. The cable or cord 15 is adapted to pass between the lugs 21 21 and ride upon the pulley 22, as 15 will be presently described. The housing 17 intermediate its ends is provided with a depending hook-shaped member 23.

In practice the curtain 9 is wound upon the roller 6, together with the cable or cord 20 15, and is held wound by fastening the cable or cord to part 23 of the head 17. The cable or cord, which is also constructed of metal, is connected to the depending hook-shaped member 23 by a fusible link 24, constructed 25 of soft solder or the like thermostatic equivalent. After the cable has been connected to the hook-shaped member 23 the weight 16 is placed within the gutter 12 of the curtain 9, and when the link 24 is melted by being subjected to undue heat from any cause the fastening means for the cord or cable is thereby 30 released and the curtain is free to unwind, the weight 16, supported by the lower end of the curtain, giving the curtain sufficient impetus to unwind the same from the roller 6. As the part of the cord or cable between pulley 20 and the weight 16, supported in gutter 12, becomes slack when the link 24 is melted and the curtain starts to unwind the weight 35 40 will be drawn off its resting-seat in the gutter and the cable or cord with the weight will swing sidewise of the window into vertical alinement and when in this vertical position will serve to accelerate the unwinding of the curtain into position for closing the window-opening. When the curtain 9 travels downwardly between the guide-plates 3 3, it will 45 50 strike the sill of the window-frame 1 and entirely incase the woodwork of the window-frame, thus preventing the same from being affected by fire or heat within the vicinity thereof. When the curtain is closed or rolled upon the roller 6, the stiffening rib or gutter 12 partially incloses the housing 17 55 and prevents birds from nesting or roosting within the housing, which might tend to interfere with the automatic operation of a curtain at the necessary time.

From the novel construction used in connection with my improved fire-curtain it will be observed that the movable or operative parts thereof are clearly protected and housed and before the metal from which the hous-

ing and the brackets are constructed can be injured the curtain would be actuated to 55 protect the window-frame.

My improved curtain can be readily constructed upon an enlarged scale and used as a safety-curtain within a theater or the like building or may be used as a fireproof partition in large stores. 70

I do not care to confine myself to the character of fusible link used in connection with the curtain, as any desirable thermostatic equivalent can be readily substituted for the 75 link.

Such changes in the construction and operation as are permissible by the appended claims may be resorted to without departing from the spirit and scope of the invention. 80

What I claim, and desire to secure by Letters Patent, is—

1. In a fire-curtain, the combination with a window-frame of a building, of guide-plates mounted upon the sides of said frame, an asbestos-covered roller journaled above said frame, an asbestos curtain connected to said roller and adapted to travel between said guide-plates, a housing mounted over said roller, a weighted cable wound upon said 85 90 roller and connecting with said housing, means to temporarily connect said cable to said housing, and means carried by said curtain to temporarily support said weight, substantially as described. 95

2. In a fire-curtain, the combination with guide-plates, of a roller journaled above said guide-plates, a fire-curtain attached to said roller, a housing incasing said roller, a weighted cable wound upon said roller, means to temporarily connect said cable to said housing, and means carried by said curtain to temporarily support said weight, substantially as described. 100

3. In a fire-curtain, the combination with 105 guide-plates, of a roller, a fireproof curtain connected to said roller and adapted to wind thereon, a housing inclosing the roller, a gutter attached to the lower end of the curtain, and adapted when the curtain is wound on the 110 roller to engage the housing, a cable connected to the roller, a weight on said cable normally supported by the gutter on the curtain, and a thermostatic element normally connecting the cable to the housing. 115

4. In a fire-curtain, the combination of a roller, a fireproof curtain connected to said roller and adapted to wind thereon, a housing inclosing the roller, a gutter attached to the lower end of the curtain, and adapted 120 when the curtain is wound on the roller to engage the housing, a cable connected to the roller, a weight on said cable normally supported by the gutter on the curtain, and a thermostatic element normally connecting 125 the cable to the housing.

5. In a fire-curtain, the combination of a roller, a fireproof curtain connected to said roller, a cord connected to the roller, a weight carried by said cord, means carried by the curtain for normally supporting said weight, and thermostatic means holding the curtain normally wound on the roller.

In testimony whereof I affix my signature in the presence of two witnesses.

THOMAS B. JACKSON.
